UNITED STATES PATENT OFFICE

2,477,119

WEATHERTIGHT CONSTRUCTION FOR
SLIDING CAR DOORSFrank Ditchfield, Cleveland, Ohio, assignor to The
Youngstown Steel Door Company, Cleveland,
Ohio, a corporation of Ohio

Application March 10, 1945, Serial No. 582,155

10 Claims. (Cl. 20—26)

1

It is an object of this invention to provide weathertight construction for the upper front corner of sliding car doors.

A further object is to provide a construction of the character set forth above which shall provide for the discharge of rain, snow, dust, cinders and the like outwardly of the doors.

A further object is to provide a weathertight construction for the upper front corner of sliding car doors in an economical manner.

Other objects of the invention will become clear as the description thereof proceeds.

In the drawings forming part of this specification.

Fig. 1 is a fragmentary elevation of a construction embodying the instant invention, parts being broken away.

Fig. 2 is a horizontal section taken on line 2—2 of Fig. 1, a portion being broken away.

Fig. 3 is a vertical section taken on line 3—3 of Fig. 2.

Fig. 4 is a horizontal section similar to Fig. 2 showing a modification of the invention.

Fig. 5 is a vertical section taken on line 5—5 of Fig. 4.

Referring to the embodiment of the invention illustrated in Figs. 1 to 3, inclusive, the numeral 10 designates a conventional Z-shaped side plate, the upstanding flange of which is broken away. The side plate includes a depending flange 11 to which the upper ends of door posts are fastened in any desired manner. The forward door post only is illustrated and is designated by the reference numeral 12.

A substantially J-shaped header 13 is carried by the side plate 10. The header embodies a vertical attaching flange 14 from the lower end of which a horizontal flange 15 projects outwardly. The flange 15 is turned upwardly to provide a flange 16. The header is extended sufficiently beyond the door posts and is secured to the depending flange 11 of the side plate and to the door posts so as to serve as a reinforcement for the car across the door opening and as a track for door lift mechanism hereinafter briefly described. Additionally, the header serves to trap foreign matter which might otherwise find its way into the car through the door opening and to this end the upstanding flange 16 of the header cooperates with a member carried by the car door to prevent any foreign matter from being blown over the flange and into the car as hereinafter explained.

The door opening defined by the side plate, the door posts and the floor of the car (not shown) is controlled by means of a door 17. This door embodies a metallic panel 18 offset outwardly adjacent to the front and rear vertical edges thereof as indicated at 19 and 20.

The margins of the panel are suitably rein-

forced. The front vertical margin is reinforced by means of a relatively sturdy member 21. This member is formed with a flange 22 which overlies and is secured to the panel as by means of rivets 23. The reinforcing member 21 also embodies a web 24, a forwardly extending flange 25 disposed substantially in the main plane of the panel and a flange 26 extending outwardly at right angles to the flange 25 and lying at the forward edge of the door. Backing plates 27 and 21A disposed substantially in the main plane of the panel are secured thereto along one margin and to the flange 25 of the reinforcing member along the other margin, thereby providing a substantially box section adjacent to the forward edge of the door.

The upper margin of the panel 18 is similarly offset as indicated at 28. This margin of the panel is reinforced by means of a member 29 which is substantially W-shaped in section. The reinforcing member 29 embodies a depending flange 30 overlapping and secured to the panel, an inwardly extending web 31, an upstanding flange 32, and an inwardly directed flange 33. A backing plate 34 is secured to the panel 18 substantially in the main plane thereof and to the flange 32 of the reinforcing member and cooperates therewith and with the panel and backing plate 27 to form a box section.

The door is adapted to be frictionally supported upon a track (not shown) fastened to the car below the door opening. Lift mechanism, designated generally by the reference numeral 35, is secured to the upper portion of the door for the purpose of elevating the door and supporting it upon anti-friction means upon the header to permit movement of the door in opening and closing directions.

With reference to Figs. 2 and 3 of the drawings, it will be observed that the inwardly extending flange 33 of the door reinforcing member 29 lies vertically above the header 13 so as to cooperate therewith in the securing of a weathertight door. A stop 36 of conventional cross section is also illustrated in these figures of the drawings. This stop embodies a substantially channel shaped portion 37 which receives the front vertical portion of the door when it is closed. A flange 38 extends inwardly from the channel-shaped portion 37 and terminates in an attaching flange 39 which is disposed parallel and secured to the front door post 12.

Prior to applicant's invention the front door stop 36 continued upwardly to the door retaining bar 40 which, as illustrated in Fig. 3 of the drawings, is Z-shaped in section and embodies an upstanding flange 41 secured to the depending flange 11 of the side plate, an outwardly extending web 42, and a depending flange 43 spaced outwardly of the header 13. With this relation-

ship between the front stop and the retaining bar, it will be apparent that the header, in the prior constructions could not extend forwardly beyond the flange 38 of the front stop and it is customary to terminate the header at this flange. Moreover, in the prior constructions in order to permit the door to close fully, it is necessary to cope the inwardly extending flange of the top door reinforcing member adjacent to the forward vertical edge of the door so that this flange would not strike against the inwardly extending flange 38 of the front stop and prevent the door from being fully closed. This coping of the inwardly extending flange of the top door reinforcing member, however, provides a substantially direct opening between the upper front corner of the door and the front stop permitting dust, cinders, rain, snow and the like, to find their way into the car through the door opening.

The instant invention eliminates this opening and substantially improves the weathertightness of the upper front corner of the door. As more clearly disclosed in Figs. 1, 2 and 3 of the drawings, the front door stop 36 is terminated below and adjacent to the header 13. The header is extended forwardly beyond the front stop and the flange 33 of the door reinforcing member 29 is permitted to extend continuously substantially to the front vertical edge of the door.

To close the opening above the header provided by this construction a plate member 44 is utilized. This member is shown more clearly in Fig. 3 of the drawings and embodies an outwardly and rearwardly directed flange 45 which is similar to and disposed upon a corresponding flange of the channel portion 37 of the front stop. The member 44 is also provided with an inwardly extending flange 46 which is disposed upon the web 47 of the channel-shaped portion 37 of the front stop and extends inwardly of the attaching flange of the header to which it is secured as by means of welding. The inwardly extending flange 46, as more clearly shown in Fig. 3 of the drawings, is coped to clear the upstanding flange 16 of the header. At its upper portion the member 44 extends to the depending flange 43 of the retaining bar 40. Inwardly of the depending flange 43 the flange 46 of the member 44 follows the inner contour of the door retaining bar and extends continuously downwardly therefrom to the outwardly extending flange 15 of the header.

It will be apparent from the foregoing construction that the inwardly extending flange 46 of the member 44 closes the header and serves as an abutment flange for the door above the door stop and that the inwardly extending flange 33 of the door reinforcing member 29 extends continuously to the flange 46 which it is adapted to abut when the door is closed. The opening in the prior constructions provided by the cope in this inwardly extending flange of the top door reinforcing member is accordingly eliminated and a materially improved weathertight construction is afforded for the upper corner of the door.

Another embodiment of the invention is illustrated in Figs. 4 and 5 of the drawings. In this embodiment the header 13 terminates at the inwardly extending flange 38 of the front stop as indicated at 48. In order to close the header 13 a member 49 is utilized. The portion of this member which extends upwardly above the front stop 36 embodies a flange 50 similar to the flange 45 of the first described embodiment of the invention and an inwardly directed flange 51 which is similar to the flange 46 hereinabove described.

with the exception that the cope formed in the flange 46 for the purpose of receiving the upstanding flange 16 of the header 13 is eliminated. Moreover, the flange 51 is extended downwardly as indicated at 52 to provide a flange extending from the channel-shaped portion 37 of the front stop to the wall of the car. In both embodiments of the invention the inwardly extending flanges of the closure members 44 and 49 are in alignment with the web 47 of the front stop.

By terminating the header 13 at the inwardly extending flange 38 of the front stop, it follows that the header is spaced from the inwardly extending flange 51 of the closure member 49. It follows, moreover, that any foreign matter which may be collected in the header may be discharged outwardly of the door stop into the space formed between the inwardly extending flange 38 of the door stop and the inwardly extending flange 51 of the closure member 49. By extending the flange 52 of the closure member 49 downwardly, as more clearly shown in Fig. 5 of the drawings, the open end of the header 13 is protected.

In all other respects the form of the invention illustrated in Figs. 4 and 5 of the drawings embodies the construction of the form of the invention illustrated in Figs. 1, 2, and 3 of the drawings.

This application is a continuation in part of applicant's co-pending application, Serial No. 465,233, filed on November 11, 1942, now Patent No. 2,415,731, patented February 11, 1947.

It will be apparent that numerous changes and modifications in the details of the invention will be clear to those skilled in the art. It is intended, therefore, that all such modifications and changes be comprehended within this invention, which is to be limited only by the scope of the claims appended hereto.

40 I claim:

1. In a railway house car having a wall provided with a door opening, a door header secured to said wall, a front door stop secured to said wall adjacent to said door opening, said door stop projecting outwardly of and terminating substantially at the bottom of said header, a door retainer secured to said wall, said retainer having a depending flange disposed outwardly of said header, and a member extending from said projecting portion of said door stop to the underside of said retainer and to said wall to close said header.

2. In a railway house car having a wall provided with a door opening, a door header secured to said wall, a front door stop provided with a flange extending from said wall adjacent to said door opening and a channel extending forwardly from said flange in spaced relation to said wall, said channel projecting outwardly of said header, said door stop terminating substantially at the bottom of said header, a door retainer extending from said wall having a depending flange disposed outwardly of said header, and a member extending from said channel to the underside of said retainer and to said wall to close said header.

3. In a railway house car having a wall provided with a door opening, a door header secured to said wall, a front door stop provided with a flange extending from said wall adjacent to said door opening and a channel extending forwardly from said flange in spaced relation to said wall, said channel projecting outwardly of said header, said door stop terminating substantially at the bottom of said header, a door retainer extending from said wall having a depending flange disposed out-

wardly of said header, and a plate member secured to the top of said channel and extending therefrom to the underside of said retainer and to said wall to close said header.

4. In a railway house car having a wall provided with a door opening, a door header secured to said wall, a front door stop provided with a flange extending from said wall adjacent to said door opening and a channel extending forwardly from said flange in spaced relation to said wall, said channel projecting outwardly of said header, said door stop terminating substantially at the bottom of said header, a door retainer extending from said wall having a depending flange disposed outwardly of said header, said header extending from said wall and terminating substantially at said flange, and a member extending upwardly from said channel to the underside of said retainer and to said wall and downwardly between said channel and said wall in spaced relation to said flange of said stop.

5. In a railway house car having a wall provided with a door opening, a door header secured to said wall, a front door stop provided with a flange extending from said wall adjacent to said door opening and a channel extending forwardly from said flange in spaced relation to said wall, said channel projecting outwardly of said header, said door stop terminating substantially at the bottom of said header, a door retainer extending from said wall having a depending flange disposed outwardly of said header, and a plate member secured to the top of said channel and extending therefrom to the underside of said retainer and to said wall to close said header, said header extending at least to said plate member.

6. In a railway house car having a wall provided with a door opening, a door header secured to said wall, a front door stop secured to said wall adjacent to said door opening, said door stop projecting outwardly of and terminating substantially at the bottom of said header, a door retainer secured to said wall, said retainer having a depending flange disposed outwardly of said header, a sliding door mounted on said car, the upper portion of said door lying between said header and said retainer flange, an inwardly directed flange at the top of said door, said door flange extending substantially to the forward edge of said door, and a member extending from said projecting portion of said door stop to the underside of said retainer and to said wall to close said header, said door flange being adapted to abut said member when said door is closed.

7. In a railway house car having a wall provided with a door opening, a door header secured to said wall, a front door stop provided with a flange extending from said wall adjacent to said door opening and a channel extending forwardly from said flange in spaced relation to said wall, said channel projecting outwardly of said header, said door stop terminating substantially at the bottom of said header, a door retainer extending from said wall having a depending flange disposed outwardly of said header, a sliding door mounted on said car having its upper portion disposed between said header and said retainer flange, an inwardly directed flange at the top of said door, said door extending substantially to the forward edge thereof, and a member extending from said channel to the underside of said retainer and to said wall to close said header, said door flange being adapted to abut said member when said door is closed.

8. In a railway house car having a wall provided with a door opening, a door header extending from said wall, a front door stop provided with a flange extending from said wall adjacent to said door opening and a channel extending forwardly from said flange in spaced relation to said wall, said channel projecting outwardly of said header and having a web substantially parallel to said flange, said door stop terminating substantially at the bottom of said header, a door retainer extending from said wall embodying a depending flange spaced outwardly of said header, and a closure member extending from said channel in line with the web thereof to the underside of said retainer and to said wall.

9. In a railway house car having a wall provided with a door opening, a door header extending from said wall, a front door stop provided with a flange extending from said wall adjacent to said door opening and a channel extending forwardly from said flange in spaced relation to said wall, said channel projecting outwardly of said header and having a web substantially parallel to said flange, said door stop terminating substantially at the bottom of said header, a door retainer extending from said wall embodying a depending flange spaced outwardly of said header, said header terminating substantially at said flange of said stop, and a closure member extending from said channel in line with the web thereof upwardly to the underside of said retainer and to said wall and downwardly between said channel and said wall in spaced relation to said flange of said stop.

10. In a railway house car having a wall provided with a door opening, a door header extending from said wall, a front door stop provided with a flange extending from said wall adjacent to said door opening and a channel extending forwardly from said flange in spaced relation to said wall, said channel projecting outwardly of said header and having a web substantially parallel to said flange, said door stop terminating substantially at the bottom of said header, said header terminating substantially at said flange of said stop, a door retainer extending from said wall embodying a depending flange spaced outwardly of said header, a sliding door mounted on said car, the upper portion of said door being disposed between said header and said retainer flange and having a flange overlying said header, said door flange extending substantially to the forward edge of said door, and a closure member extending from said channel in line with the web thereof upwardly to the underside of said retainer and to the said wall and downwardly between said channel and said wall in spaced relation to said flange of said stop, said door flange being adapted to abut said member when said door is closed.
